UNITED STATES PATENT OFFICE.

WILLIAM M. THOMAS, OF LOS ANGELES, CALIFORNIA.

ARCH CONSTRUCTION FOR CONCRETE BRIDGES.

1,356,025.

Specification of Letters Patent.

Patented Oct. 19, 1920.

Application filed March 27, 1917, Serial No. 157,660. Renewed April 19, 1920. Serial No. 375,162.

To all whom it may concern:

Be it known that I, WILLIAM M. THOMAS, a citizen of the United States, residing at Los Angeles, in the county of Los Angeles and State of California, have invented a new and useful Arch Construction for Concrete Bridges, of which the following is a specification.

This invention relates to means for mounting arches of reinforced concrete bridges in such manner as to distribute and equalize the strains or pressures at the hinges and to provide adequate and effective hinge bearings for the arch members. 15 The invention is especially applicable in connection with the three hinge arch system of reinforced concrete bridges.

Other objects of the invention will appear hereinafter.

20 The accompanying drawings illustrate an embodiment of my invention, and referring thereto:

Figure 1 is a side elevation of an arch, showing the supporting piers in section, the 25 supporting hinge being shown in incomplete condition at one end of the arch.

Fig. 2 is a vertical section on line x^2-x^2 , Fig. 1.

Fig. 3 is a vertical section on line x^3-x^3 , 30 Fig. 1.

Fig. 4 is a plan view of the parts shown in Fig. 1.

Fig. 5 is a vertical section of the crown portion of the arch members showing the 35 crown hinge.

Fig. 6 is a section on line x^6-x^6 , Fig. 5.

Fig. 7 is a view similar to Fig. 5 showing a modified form of the crown hinge.

Fig. 8 is a section on line x^8-x^8 , Fig. 7.

40 Figs. 9 and 10 are side elevations of other forms of the invention.

The arch rib to which my invention is applied is assumed to be composed of two arch beams or members 1, resting at their lower ends on piers 2 and connected at their upper ends by a crown hinge. The arch beams 1 are rounded at their lower ends to form semicylindrical bearing faces 1'. The piers 2 are of any suitable construction, and 45 each pier is provided with vertical projections or arch abutments consisting, for example, of I-beams 3 embedded in the reinforced concrete or other material of the pier. In constructing the piers they are 50 formed temporarily with horizontal bearing faces 5, and the I-beams or abutment mem-

bers 3 project above these bearing faces so that the arch members 1 may be caused to rest at their lower ends on said bearing faces and against said abutment members, as 60 shown at the right hand of Fig. 1. When the two arch members have been assembled and connected together at their upper ends by the crown hinge as hereinafter set forth, their lower ends will be supported by the 65 bearing faces 5 and by the abutment members 3 so as to hold the arch ribs in proper position. Mold boards or members 7 are then placed around the upper part of each pier, so as to surround the lower portions of 70 the arch ribs and concrete or cement indicated at 8 is then poured or run into these mold boxes so as to surround and embed the lower ends of the arch beams 1, and form a hinge bearing therefor, the concrete running beneath the cylindrical end portions of the arch rib members or beams 1, and forming a concrete cylindrical surface corresponding thereto. The cylindrical bearing face 1' of each arch beam 1 is provided with means, 80 such as metal bearing plates 11, preventing the cement of the supporting bearing from uniting with the arch beam, so as to maintain a movable hinge bearing for the arch beam. By forming the hinge bearing in 85 this manner after the arch beam has been set up, a uniform and effective bearing is secured over the entire bearing face 1' of each arch beam, so that the strains and pressures are equalized throughout the hinge 90 surface.

Means are provided at the crown of the arch for equalizing the strains by means of a hinge joint which is self adjusting to the 95 positions of the arch beams. For this purpose, the arch beams are provided with an interlocking key member which engages with both of them when they are in position, and bearing members of deformable or malleable material such as lead, are interposed between said key member and the respective arch beams so as to enable the several parts to accommodate themselves to one another and provide a uniform bearing throughout. Thus, as shown in Fig. 5, the 100 arch beams 1 are provided at their upper ends with sockets 10 for receiving a key member 12 and lead bearing plates 13 are provided between said key member 12 and metal bearing plates 14 at the bottom of said 105 sockets. Said bearing plates 14 are riveted or otherwise secured to metallic members,

for example, I-beams 15 embedded in the arch beams 1. Plates or projections 16 on the bearing plates 14 extend above and below the key member 12 to retain the same 5 in position, these members 16 also serving to confine the lead bearing plates 13 and prevent them from spreading under the pressure of the key 12 and bearing plate 14. In placing the arch beams in position, they 10 are lifted by suitable means not shown, and their lower ends are brought onto the piers, as above described, while their upper ends are raised slightly above their final position, so as to be separated sufficiently to 15 enable the key member 12 to be slipped into the sockets 10. The arch beams are then lowered into position, causing them to close upon the key member, whereupon said key member engages the lead plates 13 and any 20 tendency of the key member to bear at any particular point, causes the lead to be squeezed from such part to other parts of the bearing, so that eventually the bearing becomes uniform over the entire surface of 25 the key member and under such conditions there is no lateral or canting strain on the arch beam, such as would arise from such localized bearing and would be liable to crush the bearing parts owing to the great 30 pressures involved.

The key member 12 is shown in Fig. 5, as of rectangular cross section and is made hollow for the sake of lightness. Said key member may, however, be made circular in 35 cross section, as shown at 20 and Figs. 7 and 8, and in that case is seated in two semi-cylindrical socket members 21 in the respective arch rib member 1, and a lead plate 22 is inserted between said key member and 40 said socket members, the cylindrical walls of the socket members serving in this case to confine the yielding lead plate 22 so as to prevent spreading thereof while permitting the lead plate to adjust itself between the 45 surfaces of the key member and the sockets.

The self adjusting hinge construction above described may be used at the spring or outer hinge of the arch at each end, and as well as at the key or crown hinge. Thus, 50 as shown in Fig. 9, the arch members 24 are provided with sockets 25 in their respective ends, adapted to receive the self adjusting lead plates 26 within which engage the semicylindrical hinge or bearing members 55 27 on the respective piers 28. In place of these hinge bearings being semicylindrical they may be of any shape, for example, segmental as shown in Fig. 10, and the key member may be dispensed with, each arch 60 member 24 being provided at one end with a concave socket portion 29 and at the other end with a convex hinge portion 30 corresponding to said socket portion, an intervening lead plate 31 being provided between 65 such hinge portions and the end of the arch

and correspondingly formed hinge portions 33 and 33' on the piers. In the construction shown in Fig. 10, either of the hinge portions described may be molded conformably to the other co-operating hinge portion as 70 above described in connection with the pier hinges in Fig. 1.

What I claim is:

1. A reinforced concrete bridge construction comprising preformed arch beams, piers 75 provided with means for supporting the lower ends of said arch beams and with means for engaging the arch beams to hold the same in position, the lower ends of said arch beams being rounded to form hinge 80 faces, and concrete molded on said piers around said hinge faces on the arch beams, forming hinge bearings therefor.

2. In a reinforced concrete bridge construction, preformed reinforced concrete 85 arch beams having rounded faces at their lower ends and piers provided with means for supporting the lower ends of said beams, metallic reinforcing members in said piers extending vertically therein and engaging 90 the lower ends of said arch beams, and concrete embedding said metallic reinforcing means at said rounded hinge faces of said arch beams.

3. In a reinforced concrete bridge, the 95 combination of preformed concrete arch beams having sockets at their upper ends, a key member engaging said sockets and bearing plates of malleable material between said key member and the arch ribs, 100 said sockets in the arch ribs being formed with shoulders extending above and below said key member and confining said lead bearing plates.

4. In a reinforced concrete bridge of the 105 three-hinge arch type, the combination with the arch formed of two arch beams of a self adjusting bearing between the upper ends of said arch ribs forming a crown hinge thereof, a bearing member of malleable material between said bearing and arch beam, and means for holding said bearing member in position.

5. The method of making an arched structure, which method consists in partly 115 embedding abutment members in suitable pier-forming material, forming an arch with bearing faces at its ends, placing the arch with its bearing faces resting against the abutments, and then casting concrete around 120 the ends of the arch.

6. The method of making an arched structure, which method consists in partly embedding abutment members in suitable pier-forming material, preforming a concrete 125 arch with metal bearing plates at its ends, placing the arch with its bearing plates resting against the abutments, and then casting concrete around the ends of the arch.

7. The method of making an arched struc- 130

ture, which method consists in partly embedding abutment members in suitable pier-forming material, forming an arch in sections with bearing faces at both ends of the 5 sections, placing the sections with the bearing faces at one end resting against the abutments respectively and with the bearing faces at the other end spaced slightly apart, inserting a bearing member of malleable material between the adjacent bearing faces, 10

lowering the adjacent ends of the sections to close the arch sections against the bearing material, and casting concrete around the ends of the arch sections at the piers.

Signed at Morgantown, West Va., this 15
23rd day of March, 1917.

WILLIAM M. THOMAS.
